UNITED STATES PATENT OFFICE.

VERNE D. SANDERS, OF TULSA, OKLAHOMA, ASSIGNOR TO ECONOMY FEED WATER HEATER COMPANY, OF TULSA, OKLAHOMA, A CORPORATION.

FEED-WATER HEATER.

1,180,440.

Specification of Letters Patent. Patented Apr. 25, 1916.

Application filed May 29, 1915. Serial No. 31,173.

To all whom it may concern:

Be it known that I, VERNE D. SANDERS, a citizen of the United States, residing at Tulsa, in the county of Tulsa and State of Oklahoma, have invented certain new and useful improvements in Feed-Water Heaters, of which the following is a specification.

This invention relates to certain new and useful improvements in feed water heaters adapted for use in connection with steam boilers, both of the stationary and locomotive types.

One object of the invention is to provide a feed water heater including a heating coil arranged within the smoke box or combustion chamber of the boiler, and through which coil the water passes before it is introduced into the boiler, and means arranged within the line of feed whereby the water may be caused to flow from a source of supply to the coil and from the coil to the boiler; or from the boiler to the coil and thence back to the boiler again, so as to establish a complete circulation to prevent burning out of the coil in the event of the stoppage of the pump or injector in the feed supply; or whereby, in the event of derangement of the coil and its connections, the water may be pumped directly from the source of supply into the boiler.

Another object of the invention is to provide a feed water heater of the character described wherein a novel construction and arrangement of pipes and valves is employed to secure the desired results and whereby simplicity in both construction and operation and economy of installation with a material saving in the use of fuel will be effected. With these and other objects in view, the invention consists in the features of construction and combination and arrangement of parts more fully hereinafter described and claimed, reference being had to the accompanying drawing, in which—

Figure 1 is a view in side elevation of a portion of a steam boiler embodying my invention, portions of the wall of the boiler being broken away to more clearly illustrate the arrangement of parts; Figs. 2 and 3 are diagrammatic views illustrating the several service operations for which the apparatus is adapted; and Fig. 4 is a view similar to Fig. 1, showing a modification.

Referring now more particularly to the

drawings, the numeral 1 designates conventionally a portion of a steam boiler provided with the usual fire tubes or flues 3 and the smoke box 4. Located within the smoke box 4 is a vertical heater coil 5 formed of a compound bank of tubes, the lower or inlet end 6 of the coil being extended to the exterior and connected by the union 7 to the inlet or cold water supply pipe 8, which leads to the usual injector or pump (not shown) or other source of force feed supply. The upper or outlet end 9 of the coil also extends exteriorly and is connected by the union 10 with a return or hot water pipe 11 which extends alongside the boiler and is connected with the water containing space thereof, as indicated at 12.

Arranged within the pipe 9 is a check valve 13 and a globe or other controlling and cut-off valve 14, said check valve being arranged to open to freely permit flow of the water from the pump or injector to the coil. A controlling and cut-off valve 15, similar to the valve 14, is also provided in the return pipe 11. A short pipe section 16, which I term a circulation pipe, is connected at one end with the pipe 8 at a point between the valve 14 and the inlet end of the coil, and is connected at its opposite end with the boiler, as indicated at 17. In this circulation pipe is a controlling and cut-off valve 18 similar to the valves 14 and 15, and also located in said pipe is a check valve 19, which is adapted to open in a direction toward the boiler and close in a direction toward the cold water supply pipe 8. A by-pass pipe or conductor 20 is connected at one end with the pipe 8 at a point between the valves 13 and 14 and is connected with the delivery end of the pipe 11 at a point between the valve 15 and the boiler. This pipe 20 is provided with a controlling and cut-off valve 21 which is similar in character to the valves 14, 15 and 18.

In practice, the coil 5 is arranged within the smoke box substantially below the level of the water in the boiler, so as to insure a proper circulation being obtained. In the normal operation of the device, the feed water from the pump or injector is supplied through the pipe 8 to the coil 5, circulates through said coil and is thereby heated and thence passes through the pipe 11 into the water space of the boiler. In this operation of the device, as will be seen by reference to

Fig. 2, the valve 21 is closed and the valves 14, 15 and 18 are opened, so that the water will pass the check valve 13 and flow along the pipe 8 into the coil and thence through the pipe 11 to the boiler, as before described. If, however, the pump or injector should stop or the source of supply be otherwise cut off, as when the engine is not in use and the fire is drawn, the valves 14, 15 and 18 may be closed and the valve 21 opened, whereupon the water under pressure from the boiler will pass through the pipe 16, opening the check valve 19 in said pipe and closing the check valve 13 in the pipe 8, and will flow through the delivery end of the pipe 8 into the coil and through the pipe 11 back to the boiler, the coil being thereby filled from the boiler and prevented from burning out when the fire is again started in the fire box. Furthermore, by closing the valves 14, 15 and 18 and opening the valve 21, as shown in Fig. 3, the flow of water through the supply pipe to the coil will be cut off, as will also communication between the coil and the boiler, and the feed water will flow past the check valve 13 and through the by-pass 20 to the delivery end of the pipe 11 between the closed valve 14 and the boiler and into the latter, enabling a direct feed of the water from the source of supply to the boiler to be carried out in the event of stoppage of or damage to the coil or associated parts of the feed water connections beyond the by-pass pipe.

It will be noted that as the coil 5 is disposed wholly or substantially below the water level in the boiler, I not only insure a proper circulation but obviate any liability of the coil being burned out from the heat of the smoke box, as the coil will be kept constantly full of water in the first two operations set forth, and in the use of the by-pass may be protected wholly or to a large extent unless broken by the presence of a greater or less quantity of water therein. Inasmuch as the coil is heated from the heat within the fire box, no additional heating means is required, and as the feed water is heated prior to its introduction into the boiler by what is ordinarily waste heat, economy in the operation is obviously secured. By disconnecting the unions 7 and 10, the coil may be detached from the service

pipes and withdrawn through the door of the fire box for cleaning, renewal or repairs. By the novel construction and organization of parts disclosed it will be seen that an inexpensive type of feed water heater is provided which embodies means for maintaining a constant feed of water through the coil and supply of hot water to the boiler, while at the same time enabling the course of flow of the water to be varied for an automatic circulation through the coil in the event of the derangement of the water supplying means, or of the direct feed of water from the supplying means to the boiler in the event of derangement of the coil, thus securing safety under all conditions of service.

In the modification shown in Fig. 4 the construction is the same as that previously described, except that the coil is located in the combustion chamber 4* instead of in the fire box, which arrangement may sometimes be used.

I claim as my invention:

In a feed water heater, the combination with a steam boiler having a heating chamber, of a heater located within the heating chamber below the level of the water in the boiler, a water supply pipe connected with the lower inlet end of the heater, a return pipe leading from the upper outlet end of the heater to the water space of the boiler, cut-off valves in said pipes, a by-pass pipe connecting said supply and return pipes at a point in advance of the cut-off valves therein and provided with a cut-off valve, a check valve in the water supply pipe in rear of the by-pass pipe, and a circulation pipe connected at its upper end with the boiler below the return pipe and at its lower end with the water supply pipe at a point between the by-pass pipe and the inlet end of the heater, said circulation pipe being provided with cut-off and check valves, the controlling valve in the supply pipe being arranged in the length of said pipe between said by-pass and circulation pipes.

In testimony whereof I affix my signature in presence of two witnesses.

VERNE D. SANDERS.
